UNITED STATES PATENT OFFICE.

FRITZ FRANKE, OF BERLIN, GERMANY.

SWIMMING BLADDER.

Application filed September 13, 1926, Serial No. 135,235, and in Germany June 6, 1925.

My invention relates to a swimming-bladder for use in connection with swimming-jackets, bathing dresses, and the like, and intended to be worn upon the breast side or chest side of the body. There exist already swimming-bladders of various type but their object in general is solely to keep on the surface of the water persons who cannot swim. My improved swimming-bladder pursues, however, besides, a particular object, viz holding the body upon the water in that particular position which is the preliminary condition for swimming at all. The possibility to remain upon the surface of the water depends first of all upon a certain suitable position of the body, and only in the second case upon the swimming movements. This truth is proved by the fact that a person swimming upon the water can remain thereon without making any movement if he, or she, lies on his, or her, back and keeps his, or her, chest filled with air, the back being kept as hollow as possible. In this position of the body the lungs can expand so much and take up so much air that the specific weight of the body in the water is properly equalized. In connection with all that I point to the known fact that a person learning to swim at a line makes quite correct swimming tempi as long as he, or she, is suspended from the line, but sinks down instantly when the line is slackened. This is due solely to the incorrect position of the body.

The purpose to give a person that cannot swim that position which is indispensably requisite to enable the man etc. to make the proper swimming movements cannot be attained with the known means designed for that purpose because the respective bladders are either too large or too small, and in no way accommodated to the anatomic structure of the body. A swimming-bladder actually suited for the purpose in view must be designed with full consideration of the anatomic structure of the body, and in view of this indispensable requirement the present improved swimming-bladder is so designed and shaped that the person wearing it and assuming a horizontal position upon the water is at once positively and automatically necessitated to draw his, or her, belly somewhat inwards and to expand largely his, or her, chest which takes place without any disagreeable pressure whatever.

If the respective person assumes an incorrect position then a certain pressure reminds him, or her, at once of this occurrence and he, or she will thereby be caused automatically to re-assume the former proper position.

The swimming-bladder designed according to this invention is attached to the inner surface of the breast portion or chest portion of a bathing dress, that is to say, a pocket of suitable size and shape is attached to the bathing dress etc. at the place mentioned, and the bladder is inserted thereinto. Its proper size is such that it projects upwardly and laterally over the breast nipples, and downwardly about to the navel, so that the largest diameter of the bladder when being blown up covers the heart and the body portion surrounding the "solar plexus".

Owing to the bladder being arranged in a pocket of the bathing dress, or of a swimming jacket or the like, it is securely prevented from displacing; in other words: its proper position relatively to the body is always the same.

This improved swimming-bladder renders it possible to dispense with the usual hurtful breast girdle which hinders the important expansion of the chest and presses upon the heart muscle.

An advantage obtained by arranging the bladder inside the dress etc. consists also therein that it is no more visible from the outside. The valve hose can be put through an aperture in the upper seam of the chest pocket and then bent inwardly.

A swimming-bladder of the present improved kind need not be blown up so strongly as otherwise customary, because one of the effects of the adaptation of its shape to the chest resides therein that this latter is automatically expanded whereby the lungs are compelled to take up a larger amount of air than otherwise.

A plurality of pockets attached to the outer side of a bathing dress etc. cannot render the effect in view as they act just counter to the body assuming the proper position for swimming.

The bladder may be provided with two eyes or loops through which an expansible girdle of rubber or the like may be put, and laid around the body.

The bladder renders it possible for all persons that cannot swim and have neither

opportunity nor time to learn swimming in swimming baths to learn it by themselves in a convenient manner, quickly and without striking others with amazement. A man etc., wearing a bathing dress or the like provided with the improved bladders feels no anxiety in the water, the more, as the heart point and the "solar plexus" are insulated from the water by the bladder. Furthermore the body is caused automatically to assume the proper position in the water, i. e. that position which is a pre-supposition to swimming. This is the fundamental requirement; all other things are mere training.

The bladder is intended also for all such swimmers whose heart and kidneys are a little affected, and which suffer, therefore, from a somewhat diminished self-confidence. These nervous persons regain their former self-confidence at once, whereby their joy of exercising the swimming sport is extraordinarily increased.

The invention is illustrated diagrammatically and by way of example on the accompanying drawing on which Figure 1 is a plan of the swimming bladder designed according to this invention, Figure 2 a view of a bathing dress equipped with a similar bladder, this figure being drawn to a somewhat reduced scale relatively to Fig. 1, and Figure 3 is a section in the plane 3—3 of Fig. 2.

The shape of the bladder *a* is about that shown in Figs. 1 and 2, and its size is such that it covers the breast nipples and the "solar plexus." The bladder is provided, as usual, with an air hose *b* having attached to it a valve *b'*. These means serve, of course, for filling the bladder with air and retaining this latter therein, as usual. The bladder may be subdivided into several compart-

ments, for instance three, by ledges *c*, as usual; these compartments may communicate with each other. A subdivided bladder accommodates itself better to the chest, and is more suited to maintain the lateral equilibrium, and also the resistance to the water is reduced by that provision. *d* denotes loops through which a rubber girdle may be drawn.

The bladder is located in a pocket *e* provided on the inner breast side or chest side of the bathing dress *f*. The pocket *e* is, however, in fact, an inverted pocket in that it is closed at its upper rim and open at its lower rim; it is provided with slots *g* through which the loops *d* extends outwardly in order to receive the rubber girdle *h*. This girdle serves also for closing the pocket at its open lower rim and for securing the bladder in its position within the pocket.

The bladder need be blown up only moderately in that it does not require a larger amount of air than a grown-up person can take up in his, or her, lungs.

I claim:

In combination with a bathing dress, swimming jacket, or the like, a pocket provided on the inner surface of the breast side or chest side of the respective garment, and a swimming bladder arranged in said pocket, the size of the pocket and of the bladder being such that this latter covers the body portion extending from the chest, or the breast nipples, to the navel, or the "solar plexus," and the shape of the said bladder corresponding to the anatomic structure of the body and having the greater capacity of the bladder adjacent the breast, substantially as described.

In testimony whereof I affix my signature.

FRITZ FRANKE.
